RADIO AMPLIFICATION

Application filed February 12, 1927. Serial No. 167,829.

My invention relates generally to electrical systems involving rectification, and, while not limited in its application or use, has particular reference to radio systems in which no frequencies exist other than those intercepted by the antenna and those resulting from rectification and amplification.

The invention consists essentially in a multistage amplifier and the object of the invention, broadly stated, is to effect simultaneous rectification and amplification of all frequencies present in the wave form of current or voltage that is applied to the input of the amplifier.

This and other important objects of the invention will more clearly appear from the description that follows.

For purposes of illustration, I have shown diagrammatically, in the accompanying drawings, circuits suitable for carrying my invention into effect.

Fig. 1 illustrates a typical circuit for the actual application of the vacuum tube to radio reception of voice or telegraph signals; Fig. 2 is a curve diagram showing the relation between the plate current and grid voltage and between grid current and voltage; Fig. 3 is a curve diagram showing the application of the proper biasing potential to the tube circuit whereby the wave form of the currents in the output circuit conform closely to the wave form of the voltage applied to the grid; Fig. 4 is a curve diagram showing, as a result of making the grid less positive, relative to the filament, greater variation between the wave form reproduced in the plate circuit and the wave form impressed on the grid circuit;

Fig. 5 is a curve diagram of the wave form of the currents in the various parts of the circuit shown in Fig. 1;

Figs. 6^a and 6^b represent two simple circuit arrangements embodying the principles of my invention;

Fig. 7 shows a further development of my invention, employing four tubes; but only the first and last of which serve as rectifiers;

Fig. 8 illustrates a modification of my invention in which each tube acts simultaneously as a rectifier and as an amplifier; and

Fig. 9 illustrates a further development of the circuit arrangement of my invention, in which a head set is employed for each stage of vacuum tube amplification.

In the present day reception of radio signals and particularly "broadcast" reception, a much higher degree of amplification is desirable than has been available in the past. To meet this need, highly developed amplifiers of the audio frequency and radio frequency types have been produced. These two types of amplifiers are essentially the same, in so far as constituent parts are concerned, and are, in the last analysis, combinations of vacuum tubes and transformers or other interconnecting devices, which act as the means for the transfer of the energy liberated by each tube in the sequence to the tube next in sequence.

The vacuum tube amplifier, consisting of vacuum tubes and interconnecting devices, which may be termed generically inter-valve connectors, functions as it does by reason of the fact that the vacuum tube has the desirable characteristics of liberating in its output circuit, usually termed the plate circuit, more power than is supplied to its input circuit, usually termed the grid circuit.

Assuming a typical set of connection, as shown, for example, in Fig. 1, it will be noted that both the input and output circuits are provided with separate sources of direct current at C and B respectively. The functions of these two sources are distinctly different, however, in that while the plate circuit current supply is designed to be the source from which the output power is drawn, the grid circuit current merely serves to give a preliminary adjustment to the grid of the tube, to make its operation most effective. No power is drawn from this source of supply, but, on the other hand, if any direct current flows, it flows in a direction to oppose the voltage of the battery and hence serves to charge the battery instead of discharging it, as is the case in the plate battery.

The action of the tube as an amplifier will be best understood from the characteristic curves shown in Fig. 2. These curves show the relation between plate current and grid

voltage and between grid current and voltage; the two curves being plotted to the same scale. It will be noted that the axis $y-y$ represents the zero of plate and grid currents, while the axis $x-x$ represents the zero of grid potential, where grid potentials are expressed relative to the negative end of the filament. Thus, when the battery C , of Fig. 1 is reduced to zero the current in the grid circuit becomes zero and the plate current has some value as shown in the plot of Fig. 2 at a .

If now the grid is made positive relative to the filament terminal by the insertion of a battery or by other means, both the plate and grid currents will increase, the rate of increase in the plate current with applied voltage, being somewhat greater. If the grid is made more negative relative to the filament, the currents will decrease. Any voltage that is caused to act on the grid circuit will then cause a change in the plate current.

If the proper choice is made of the constant voltage applied to the grid, usually termed the "biasing voltage", the wave form of currents in the output circuit will conform very closely to the wave form of the voltage applied to the grid. This condition is shown best in Fig. 3, where the potential of the grid is very positive relative to the filament. On this plot the two characteristic curves of the tube are again shown and the line $a-a$ represents the direct voltage applied to the grid when the connection from the input circuit is completed to the negative side of the filament.

When an alternating voltage is applied to the input terminals of Fig. 1, of the magnitude shown by the sinusoid plotted vertically about the axis $a-a$ of Fig. 3, two currents i_p , i_g are brought into being. These currents have been determined by the construction and plotted in Fig. 3. It will be noted that both the plate and grid currents reproduce the applied wave form of the voltage with remarkable precision, in that they both approximate the sinusoidal form very closely. It will be further noted that the magnitude of these currents is distinctly different, the plate current being many times the grid current. Assuming the value of the useful resistances through which these currents flow, to be of the same order of magnitude, it is obvious that the tube makes available in its output circuit a greater amount of power than is supplied to its input circuit and that it is, therefore, an amplifier and that the amplification is effected with no great change in the electrical wave form of the current or voltage being amplified. That is, of course, the ideal type of amplifier since it reproduces, quite faithfully, any electrical wave form supplied to it.

When the grid is made less positive relative to the filament than in the above case such as in the instance where one connection of the

input circuit is made to the negative end of the filament, the wave form reproduced in the plate circuit is not as faithful a reproduction of the wave form impressed on the grid circuit, as in the above case. This characteristic is shown in Fig. 4. Here the same characteristic curves of Figs. 2 and 3 are shown and the same magnitude of alternating current grid voltage is plotted about the axis $a-a$ (negative end of the filament) and by the same construction of Fig. 3, the grid and plate currents are plotted. It will be observed, however, that while the magnitude of the grid current, caused to flow by the applied voltage, is very markedly decreased over that of Fig. 3, the plate current is reduced in only a minor degree. Thus the tube becomes a more effective amplifier under these conditions than under those conditions where the biasing potential is omitted since the ratio of output power to input power is greater in this latter case. The wave of the plate current is, however, distinctly distorted; the lower half of the wave of plate current being smaller in amplitude than is the upper half. Thus the plate current is more nearly symmetrical about an axis $d-d$ and hence is equivalent of a sinusoid about this axis plus a direct current component as indicated by the distance along $a-a$ between $c-c$ and $d-d$, in addition to the constantly flowing direct current as indicated by the distance along $a-a$ between $c-c$ and $y-y$.

This condition, in which a direct current is brought into being by the application of an alternating voltage to the grid, in addition to the plate current always present in the plate circuit of the tube, is known as rectification and is that property which makes the vacuum tube useful as a rectifier or detector of alternating current.

The details of its action, in radio circuits, need not be discussed in detail but it must be understood that the effectiveness of any device as a detector or rectifier, is directly proportional to the degree in which it brings into being a direct current in the output circuit, by the application of an alternating voltage to the input circuit.

Where the vacuum tube is to be used as a detector primarily, it is necessary that the rectification be made more complete than is shown in Fig. 4. This is usually accomplished by the introduction of the C battery shown in Fig. 1, which allows of the grid being made sufficiently negative to greatly augment the rectifying distortion of Fig. 4.

In the actual application of the vacuum tube to radio reception of voice or telegraph signals, this rectifying distortion is made use of for separating out the voice or signal frequency from the radio carrier frequency, so that the voice or signal frequency may be made use of in the telephone or other indicating device. A typical scheme of connec-

tions is shown in Fig. 1. This consists of a tuning system 10 for tuning the antenna 11 to the frequency being received, a vacuum tube detector 12 with auxiliary batteries and 5 a pair of telephones 14 and by-pass condenser 15. The by-pass condenser 15 is sometimes omitted in practice, since the ordinary telephone cords have all the characteristics of a by-pass condenser.

10 The wave form of the currents in the various parts of the circuit are shown in Fig. 5, in which "a" shows the wave form of the antenna current for a damped wave signal, such as might be secured in spark or telephone reception. This consists of currents of radio frequency of varying amplitude; the variation of amplitude being determined by the character of the transmitter. "a" is also obviously the wave form of the voltage applied 15 to the grid. "b" is the wave form of the current in the plate circuit of the tube, which current is forced to pass through the joint paths of the telephones and the by-pass condenser. This latter current is broken up into 20 two components by the telephone-condenser combination, as shown in "c" and "d". The radio frequency component is prevented from passing through the telephones because of the high impedance of the ordinary telephones to radio frequencies and passes 25 through the by-pass condenser, which can quite easily be made to have a very low impedance to this current. The second component current "e", which may be viewed as 30 being the two other component currents "e" and "f", passes through the telephones and makes itself evident as the signal. The low frequency component "e", is of course, the activating cause in the telephone response, while the telephones merely serve as a ready path 35 for the flow of the direct current of "f".

Special means are sometimes provided whereby the D. C. component of the telephone current is by-passed by a circuit outside of 40 the telephones 14. This is not essential nor, under certain conditions, desirable, and for present purposes, the effective telephone current may be considered as merely the low frequency component "e".

50 It will be observed, from the wave form of "b", that the vacuum tube was assumed to be a perfect rectifier, in that one-half of the impressed wave form was entirely lost through rectification. While this is never realized, 55 the curves show what may be expected in the ideal case, and so sufficiently approach the conditions of practice to make valid the useful conclusion drawn from examination of them.

60 It will be observed further that in the simplified circuit arrangement of connections referred to, there is a radio frequency current in the plate circuit of very considerable magnitude and that this current is by-passed and 65 has no effect on the telephones 14.

Based on the above stated fact, my invention consists essentially in means for making useful this normally by-passed radio frequency current.

In previous systems of amplification, the 70 radio frequency component of "d" (Fig. 5) is completely lost through the shunt path provided by a by-pass condenser in the output circuit of the electron tube or where such a condenser is not supplied through the inherent capacity of the transformer winding and is no longer effective in causing signals in the telephones.

I have discovered that this radio frequency current can be utilized to advantage in the 75 reception of radio signals, to greatly augment the signals that are made available to the telephones, without increasing the number of tubes over what is normally required for the ordinary voice frequency amplification.

This is due to the fact that practical conditions cause a great departure from the ideal conditions, shown in the above figures.

I have found that even the most effective 80 detectors of the vacuum tube or other types, give a far greater ratio of radio frequency current to low frequency signal current in the output, than is shown in the case of the ideal rectifier of Fig. 4, and that by making 85 the energy of this radio frequency current, available to the telephones, in the form of low frequency current, a greatly augmented signal may be secured.

I have found further that in the ordinary 90 radio frequency amplifier, when adjusted for maximum amplification, the departure of the wave form from the faithfulness of Fig. 3, is so great, as to introduce a very readily noticeable magnitude of rectified current. 95 This comes about through the fact, that while the condition for faithful reproduction of wave form may be very nearly realized by means of the ordinary vacuum tube, the efficiency of amplification—that is to say, the ratio of output to input power,—is greatly augmented if the grids of the amplifier tubes are made more negative than for the conditions of Fig. 3. Thus each succeeding 100 step of amplification becomes a rectifier, as well as an amplifier and an amplifier operating at the greatest possible ratio of output to input power, in which each tube acts as a detector, almost as effectively as if especially adjusted for that purpose. The degree to which the tube rectifies is, of course, determined by its grid potential and may be, therefore, quite easily controlled and compensated.

I have found that a vacuum tube amplifier, 105 devised to make use of the successive rectifications which occur in its vacuum tubes, produces a degree of amplification not possible under the conditions of the present well known circuits shown in several figures 110

above discussed. I have termed this method of amplification "duplex amplification" since both radio frequency and audion frequency amplification occur in each tube, including the rectifier.

An amplifier embodying the principles of my invention is shown in Figs. 6^a and 6^b and it will be noted that in this amplifier each tube performs the double function of an amplifier and a detector. The first tube 16 of the series rectifies the voltage applied to it, as described above, and has in its plate circuit 17, a current of the form shown at *b*, in Fig. 5. It may be caused to rectify by the use of 13 a biasing voltage from a biasing battery C as shown in Fig. 6^a or the biasing voltage 15 may be secured by means of the grid leak and condenser as shown in Fig. 6^b at 18.

The method of amplification does not, of course, in any way depend upon the method of securing rectification but depends only on there being present in the plate circuit both the low and radio frequency components of the signal current, both of which are amplified. The more nearly the rectification of the first tube approaches the ideal shown at *b* in Fig. 5, the more effective will the device be, but any departure from the ideal rectifier will be counterbalanced by the amplification of the next tube 19.

Since the two tubes 16 and 19 are interconnected by both radio frequency transformers 20, and audio frequency transformers 21, both the radio and audio frequency components will be present in the voltage applied to the second tube 19. This tube 19 amplifies both frequencies and rectifies, as did the first tube 16, which results in another current, having both radio and audio frequency components. It will be observed that the audio frequency transformers 21 are provided with by-pass condensers 23 so that the radio frequency current may pass with little impedance. These condensers 23 may be omitted when there is sufficient inherent capacity in the audio frequency transformers themselves. A grid condenser and grid leak 26 is shown interposed in the input circuit of tube 19.

In Fig. 7 is shown another form of my invention applied to a four tube amplifier. It will be observed that only the first and last tubes 16 and 19 respectively are used as rectifiers, the intermediate tubes 24 and 25 merely serving as amplifiers of both the radio and audio frequencies. The intervalve radio frequency transformers are shown at 20 between each of the four stages and the audio frequency transformers interlinking the stages are shown at 21 with by-pass condensers 23 connected therewith.

The same principle of the simultaneous rectification and amplification of the radio and audio frequencies may be applied to any amplifier, and by its use a given number of

stages of amplification may be made to give a degree of amplification far in excess of any that could be secured without the use of the rectifier-amplification circuit herein disclosed.

In Fig. 8 is shown another application of the same principle. In this circuit, each of the tubes 16, 24 and 19 acts simultaneously as rectifier and amplifier. It is particularly useful where the signal being received is of such a magnitude as to cause the voltage applied to the last grid, in such a circuit as is shown in Fig. 8, to exceed the efficient capacity of the tube for rectification. This may come about through the fact that the effective input voltage capacity of a vacuum tube rectifier is usually much less than its effective input voltage capacity as an amplifier. Grid leaks and grid condensers 18, 27 and 26 are provided in each input circuit. The radio frequency coupling transformers are shown at 20 and the audio frequency inter-valve transformers are shown at 21. In the circuit, shown in Fig. 9, since each tube 16, 24, 25 and 19 acts as a rectifier and thereby augments the audio frequency component of the plate current by the amount of its rectification, it serves to operate each successive tube, so far as rectification is concerned, most effectively.

Fig. 9 shows another application of the method for the operation of as many headsets at 28, 29, 30 and 14 as there are stages of vacuum tube amplification. The radio frequency component in each tube is passed on to the next tube for rectification through transformers 20 and the audio frequency component is delivered to the headset in each tube plate circuit, where it makes itself evident as a signal. By-pass condensers 31, 32 and 33 are shown in shunt with telephones 28, 29 and 30 but telephones 14 are not provided with a by-pass shunt.

Having thus described my invention, what I claim is:

1. In a multi-stage amplifier system, a plurality of electron tubes each having input and output circuits, means for adjusting each of said tubes for operation simultaneously as rectifiers and amplifiers of signaling energy impressed upon said tubes, and coupling means between the input and output circuits of said tubes comprising independent transformer systems each responsive to different frequencies, one of the transformer systems between each of said tubes having means for by-passing the frequencies for which the other transformer systems are responsive, and means in the output circuit of the last of said electron tubes responsive to the integral effects of the rectification and amplification properties of all of said tubes.

2. In a multi-stage amplifier system, a plurality of electron tubes each having input and output circuits, a grid leak and shunt

connected condenser disposed in each of said input circuits, a pair of transformers inter-linking the output circuit of one tube with the input circuit of a succeeding tube, each transformer having primary and secondary windings, the windings of one transformer being responsive to one range of frequencies and the windings of the other transformer being responsive to a different range of frequencies, each of said tubes operating to simultaneously rectify and amplify signaling energy impressed thereon, and means connected with the last output circuit for integrating the effects of all of said tubes.

3. An amplifier on which is impressed a band of radio frequency carriers modulated by a band of signal frequencies, two vacuum tubes having input and output circuits; means for adjusting the tubes to act as rectifiers and amplifiers simultaneously; coupling means between the output circuit of the first tube and the input circuit of the second tube comprising two independent inductance systems, one of said inductance systems being responsive to the band of radio frequency carriers, the other of said inductance systems being responsive to the band of modulating signal frequencies and having means for bypassing the band of radio frequency carriers, means associated with the output circuit of the second tube responsive to the integral effects of rectification and amplification of both said tubes.

4. An amplifier on which is impressed a band of radio frequency carriers modulated by a band of signal frequencies, two vacuum tubes having input and output circuits, means for adjusting the first tube to act as a rectifier and amplifier simultaneously, coupling means between the output circuit of the first tube and the input circuit of the second tube comprising two independent inductance systems, one of said inductance systems being responsive to the band of signal frequencies appearing in the output circuit of the first tube acting as a rectifier, the other of said inductance systems being responsive to the band of radio frequency carriers passed through said first tube and appearing in the output circuit of said tube, means to bypass the band of radio frequency carriers around the inductance system which is responsive to the band of signal frequencies, means for adjusting the second tube to act as a rectifier and amplifier simultaneously, means associated with the output circuit responsive to the band of signal frequencies rectified by said second tube from the band of modulated radio frequency carriers passed through the first tube into the second and also responsive to the band of signal frequencies rectified by the first tube from the impressed band of modulated radio frequency carrier and passed through and amplified by the second tube.

5. An amplifier on which is impressed a band of radio frequency carriers modulated by a band of signal frequencies, two vacuum tubes having input and output circuits, means for adjusting the first tube to act as a rectifier and an amplifier simultaneously, coupling means between the output circuit of the first tube and the input circuit of the second tube comprising two independent transformer systems, one of said transformer systems being responsive to the band of signal frequencies appearing in the output circuit of the first tube acting as a rectifier, the other of said transformer systems being responsive to the band of carriers passed through the first tube and appearing in the output circuit of said tube, means to bypass the band of radio frequency carriers around the transformer system which is responsive to the band of signal frequencies, means for adjusting the second tube to act as a rectifier and amplifier simultaneously; means associated with the output circuit responsive to the band of signal frequencies rectified by said second tube from the band of modulated radio frequency carriers passed through said first tube into the second and also responsive to the band of signal frequencies rectified by the first tube from the impressed band of modulated radio frequency carriers and passed through and amplified by the second tube.
